UNITED STATES PATENT OFFICE.

WILLIAM PFILE, OF FREEPORT, ILLINOIS.

CONCRETE-MIXER.

1,103,685.

Specification of Letters Patent. Patented July 14, 1914.

Application filed March 18, 1913. Serial No. 755,152.

To all whom it may concern:

Be it known that I, WILLIAM PFILE, a citizen of the United States, residing at Freeport, in the county of Stephenson and State of Illinois, have invented certain new and useful Improvements in Concrete-Mixers, of which the following is a specification.

This invention relates to concrete mixing machines of a type in which a revolving cylinder is employed to mix the concrete.

The object of the invention is to construct a mixer of this type in which the mixing cylinder shall be suspended and carried by chains that form driving means for rotating the cylinder.

In the accompanying drawings: Figure 1 illustrates my improved concrete mixer mounted on a carrying truck, the view showing the discharge end of the mixer. Fig. 2 is a longitudinal section through the cylinder as taken on the line 2—2 of Fig. 1. Fig. 3 is a view of the mixer from the front end of the truck.

A concrete mixer of my improved construction may be positioned stationary or upon a movable truck as illustrated. The truck frame 3 is supported by the rear carrying-wheels 4 and front dirigible wheels 5. The concrete mixer is mounted on the truck 3 to the forward end thereof to leave room for a suitable form of engine to be mounted on the rear of the truck to rotate the mixing cylinder.

Two standards 6 of angle iron are bolted to opposite sides of the frame 3, forming arch supporting means which carry the cylindrical mixer. Journal bearing brackets 7 are bolted to the top of standards 6 and carry the drive-shaft 8. Sprocket-wheels 9 are fixedly mounted on shaft 8 adjacent the end bearings 7.

The cylindrical mixer 10 is formed of metal plate and is conical in shape. At the feed end of the mixer is an angle mouth piece 11 whose sides converge inward to the opening therein. Angle iron ribs 12 secured to the inner side of the mixer form strengthening means and also assist in agitating the concrete. A spiral plate 13 having an opening at its center is carried transversely in the mixer and assists in agitating the contents being mixed. A horizontally disposed water pipe 21 supported by bracket 22 bolted to standards 6 has a plurality of spaced openings through which water is fed to the contents after the same have been dry

mixed at the entrance side of plate 13. Sprocket-wheels 14 are fixedly carried at each end of the mixer in alinement with the sprocket-wheels 9, both of sprocket-wheels 14 being of the same diameter. Endless chains 15 connect the sprocket-wheels, suspending the mixer with its axis horizontal, these chains forming the sole supporting means for the mixer. Channel tracks 16 are mounted on the peripheral face of the mixer to the outer side of the sprocket-wheels and form guides for rollers 17 which are carried by the adjustable brackets 18 pivoted from pins 19 on the standards 6, these rollers 17 guiding and holding the mixer from any swinging movement from their suspension support. A pulley wheel 20 is fixed on shaft 8 and is adapted to be driven by an engine carried at the rear end of the truck.

In operation, the cylinder is revolved slowly through the over-head drive, and gravel, sand and cement are fed to the cylinder through the narrow end thereof. The mouth plate 11 because of its conical shape, holds the contents being mixed within the cylinder, preventing leakage at the feed end. The contents are thoroughly dry mixed in the compartment to the entrance side of the spiral plate, and as the cylinder revolves, that which is thoroughly mixed dry passes through the opening in the center of said plate and is mixed with water fed from pipe 21, the contents moving because of the downward slope of the bottom of the cylinder, to the open end thereof, from which they are discharged in the form of concrete.

It will be seen that by suspending the mixing cylinder by chains that serve as means for rotating the cylinder, that a very simple and easy running mixer is obtained. The few working parts involved in such a construction makes the mixer inexpensive in its manufacture and sale, while not depreciating in the least from the efficiency of the resulting work.

I claim as my invention.

1. A concrete mixer comprising a rotatable conical cylinder having the opening of its smaller end reduced by a flange extending inwardly from the cylinder casing, a spiral plate located in the cylinder dividing same into an intake and discharge compartment, said plate adapted to retain the bulk of ingredients in the entrance compartment during certain part of operation, baffle plates extending inwardly from the cylinder casing

in both compartments, the cylinder being mounted with its axis horizontal so that said ingredients will be thoroughly dry mixed before passing said spiral plate, and means for supplying water in the discharge compartment from central and spaced points therein.

2. A concrete mixer comprising a rotatable cylinder having an entrance and discharge end, the opening of the entrance end being reduced by a flange extending inwardly from the cylinder casing, a spiral plate located in the cylinder dividing same into an intake and discharge compartment, said plate adapted to retain the bulk of ingredients in the entrance compartment during a certain portion of operation, baffle

plates extending inwardly from the cylinder casing in both compartments, the cylinder being mounted with its lower cylinder 20 wall inclined with its entrance end the highest to allow said retained ingredients to be thoroughly dry mixed before passing said spiral plate, and means for supplying water in the discharge compartment from a 25 central point therein.

In testimony whereof I have hereunto set my hand in presence of two subscribing witnesses.

WILLIAM PFILE.
